UNITED STATES PATENT OFFICE.

WALTER LYTTON AND PHILIP E. EDELMAN, OF CHICAGO, ILLINOIS, ASSIGNEES, BY
MESNE ASSIGNMENTS, TO SAID LYTTON.

RADIO AND PHONOGRAPH COMBINATION SWITCH.

Application filed October 20, 1924. Serial No. 744,703.

This invention relates to combined radio and phonograph systems and has for its object the production of a single amplifying horn for receiving and transmitting, either 5 simultaneously or successively, sound waves from phonograph and radio reproducers. A particular object of the invention is to provide convenient means for operating the mechanism which controls the coaction of 10 the respective reproducers with the amplifying horn. In order to set in operation a radio receiving system it is usual to close a switch, such as the switch in the filament circuit, and one object of our invention is to 15 provide automatic means for selecting the reproducer which is to coact with the horn when the radio operating switch is either opened or closed. Other objects of the invention will be apparent from a consideration 20 of the accompanying drawings, and the following description thereof:

Of the drawings Fig. 1 is an elevation, partly in section, of a combined radio and phonograph system which embodies features 25 of our invention; Fig. 2 is a diagrammatic view of the radio system; Fig. 3 is an elevation, partly in section, of a modified form of apparatus; Fig. 4 is an enlarged detail view of the operating mechanism of the apparatus 30 of Fig. 4; and Fig. 5 is a diagrammatic view of the radio system of Fig. 4.

Our invention comprises a cabinet 10, which is adapted to inclose the radio and the phonograph mechanisms, and also the amplifying horn 11 which has the double purpose 35 of receiving sound waves from the two reproducers, either simultaneously or successively. The horn has an inlet 12 for receiving the sound waves from the radio reproducer, or loud speaker, 13, and another inlet 40 14 for receiving sound waves from the phonograph reproducer 15 through the ordinary tone arm 16. Journaled in the horn 11, preferably between the two inlets, is a stem 17, and a vane or valve 18, fixed to the shaft, is adapted to close part way or entirely either of the inlets 12 and 14. Obviously when one of these inlets is closed 45 sound waves can pass undisturbed through the other inlet. Or if the valve is positioned midway between the two closed positions, sound waves can pass through either of the inlets or through both at the same time.

We provide resilient means for holding 50 the valve in the position for automatically

closing the radio inlet, so that normally the phonograph inlet is open. But we provide automatic means for opening the radio inlet and closing the phonograph inlet when the radio system is set in operation by means 60 of the ordinary controlling switch. If it is desired to use both reproducers simultaneously means are provided for holding the valve in its midway or other desired positions.

Any suitable resilient means may be provided for holding the valve normally so as to close the radio inlet. We prefer for the purpose an arm 20 fixed to the valve stem 21 outside of the horn, and a spring 22 which connects the arm 20 with the frame 23 of the cabinet, so that the spring 22 normally holds the valve 18 in its position to close the radio inlet. When the radio system is to be used, however, it is necessary to open the 75 radio inlet, and for this purpose we provide means which automatically operate the valve when the switch 24 closes the circuit of the filament 25. These means comprise a circuit 26 which is connected to the battery 27 of the filament circuit, either in series with the filament circuit, or in parallel therewith as indicated in Fig. 2. In the circuit 26 is connected a solenoid coil 28. When the switch 24 is closed the coil 28 will be energized by the battery 27, and the iron core 29 will be pulled downwardly into the coil, carrying with it the arm 20, and thus closing the inlet 14.

Any suitable radio system may be used. 80 The system illustrated in Fig. 2 is an ordinary three tube system having the reproducer, or loud speaker 13.

In operation if the phonograph is to be used it is necessary only to operate it in 85 the ordinary manner, as normally the inlet 14 will be open. If it is desired to operate the radio system it is necessary only to close the filament switch in the ordinary manner, and the radio inlet 12 will be opened and the 90 phonograph inlet closed; so that the operation of the entire mechanism, so far as concerns the successive use of the reproducers with the single horn, is automatic.

If it is desired to use the two reproducers simultaneously we provide means for holding the valve in its midway position. These means comprise a stop 31 which is positioned so as to prevent the arm 20 from moving downwardly further than the mid- 105 110

way position when the stop is pushed upwardly; the projection 32 on the end of the arm then strikes on the stop 31. When the switch 24 is closed the solenoid 28 will hold 5 the switch in the midway position so long as the radio system is used. If it is desired then to use the radio system alone it is necessary only to pull out the stop and the arm 10 will be forced downwardly by the solenoid.

Figures 3 to 5 illustrate a modification of our automatic system. As is well understood the switch 24 is ordinarily operated by means of a knob on a panel board, merely 15 rotating the knob one way closes the switch, and rotating it the other way opens the switch. In this modified system we provide means for operating the valve 18, instead of operating the switch 24 directly, and provide 20 automatic means for operating the switch when the valve is operated. Any suitable means may be used for operating the valve; but we prefer for the purpose the knob 35 which is mounted on the valve stem 25 36, the valve 18 being fixed to the stem, and the stem being journaled in the junction of the two inlets 12 and 14 of the horn. The knob 35 may be positioned in any convenient point of the cabinet, but we prefer to 30 have the stem 36 project through the dial board 37, so that the valve can be operated by rotating the knob 35 on the panel board substantially in the same manner as the switch of the filament circuit is ordinarily 35 operated. In this instance we prefer to use a balanced valve, and for this purpose provide a weight 38 mounted on the arm 39 which is fixed to the stem 36, so that the valve 18 will remain in any position desired. 40

Any suitable means may be used for setting in operation the radio system when the valve is operated by the knob 35. We prefer for this purpose a switch 40, the terminals of which are connected to the wires 41

of the filament circuit. When the knob 35 is operated to open the radio inlet 12, the switch 40 will be automatically operated to close the filament circuit 41; and when the valve 18 is returned to the position to close the inlet 12 the switch 40 will be opened. 50

In order to operate both reproducers simultaneously it is necessary only for the operator to rotate the valve to its medium position and the arrangement of the switch 40 is such that the filament circuit will then be closed. It will be understood that the switch 40 comprises a wheel 42, the peripheral surface of which is composed of a non-conducting substance 43 except for the conductor 44, 60 and when the wheel is rotated so that the two brushes 45 are on the conductor 44, the circuit 41 will be closed. And the angular position of the conductor 44 is such that the circuit will be closed whenever the valve 18 is in the midway position as well as in the position to close the inlet 12. But when the valve is raised above the midway position the circuit will be opened. 65

We claim as our invention:

1. An amplifying horn having an outlet and two inlets, means for closing either of said inlets, resilient means tending to hold said valve in one closed position, means for holding said valve in its other closed position, and means for holding said valve in an intermediate position. 70

2. An amplifying horn having an outlet and two inlets, a sound reproducer operatively connected with each of said inlets, a valve for closing either of said inlets, resilient means for holding said valve in one closed position, means for holding said valve in its other closed position, and means for holding said valve in an intermediate position. 80

In testimony whereof we hereunto set our hands.

WALTER LYTTON,
PHILIP E. EDELMAN.
